LAURITZ HARALD JOHAN THEODOR BJÖRNSEN, OF COPENHAGEN, DENMARK.

ELECTRICAL TIME-SWITCH.

1,335,709.

Specification of Letters Patent. Patented Mar. 30, 1920.

Application filed August 29, 1917. Serial No. 188,846.

To all whom it may concern:

Be it known that I, LAURITZ HARALD JOHAN THEODOR BJÖRNSEN, subject of the King of Denmark, residing at Copenhagen, Denmark, have invented certain new and 5 useful Improvements in Electrical Time-Switches, of which the following is a specification.

The present invention consists of an electrical time switch of the kind where the heat produced by an electrical current causes a body to expand, the said expansion and subsequent contraction being utilized to close or 10 interrupt an electrical circuit.

15 The essential feature of the invention is a heat-operated member closing, by means of the heat produced by the operating current, the circuit for another heat-operated member which thereby closes the main circuit.

20 On the drawing is shown, in diagram, one manner of constructing the invention as utilized for a so-called staircase automaton.

25 1 and 2 are the feeding wires, positive and negative respectively, 3 the lamps, 4 the push-button switches and L, M, P, T the connecting terminals. 5 and 6 are two metal bars firmly interconnected at both ends, one of the bars facing an incandescent lamp 7, 30 so that the latter when burning heats the bar 5 which, by the elongation produced thereby, moves a contact 8 toward an adjusting screw 9.

35 15, 16, 17, 18 and 19 are a contact system corresponding to 5, 6, 7, 8, 9.

The apparatus acts in the following manner:

40 By the depression of one of the push-buttons 4, a circuit is closed from the positive terminal P and through the switch 4, the terminal T and the incandescent lamp 17 to the negative terminal M. The heat radiating from the lamp will heat the metal bar 15 and thereby, within a short time, it 45 will bring the contact piece 18 into contact with the screw 19. By this contact, a new circuit is closed from the positive terminal P and through the contacts 18, 19 and the incandescent lamp 7 to the negative terminal M. The heat radiating from the incandescent lamp 7 will soon bring the contact piece 8 into contact with the contact screw 50 whereby a new circuit—the main circuit—is closed from the terminal P through the lamps 3, the connecting terminal L, the

heat-operated member 5, 6 and contacts 8, 9 to the terminal M.

As soon as the lamps 3 begin to burn, the push-button 4 is released, whereby the lamp 17 is extinguished, and the bar 15 begins to 60 cool down. After some time, the contact 18 moves away from the contact screw 19, whereby the circuit between the incandescent lamp 7 is broken, and the bar 5 begins to cool down. When the cooling has pro- 65 gressed so far that the contact 8 is brought out of contact with the contact-screw 9, the main current is interrupted and the lamps 3 are extinguished.

70 Experiments have shown that it is practicable to reduce to about one second the time during which it is necessary to depress a push-button in order to cause the lamps 3 to burn and, further, that by adjusting the screws 9 and 19 the length of time during 75 which the lamps continue to burn may be varied between 1 and 5 minutes or, if desired, between still wider limits.

75 Ordinarily, the pressure on the push-button 4 will be released as soon as the lamps 3 begin to burn. If it be desired, however, to have the lamps burning somewhat beyond the normal period, it is only necessary to keep the button depressed for a short time—for instance one second—after the lamps 80 have been lighted. Besides, it is feasible, at any time during a burning period, to initiate a new period by depressing a push-button 85 once more.

90 If one of the push-buttons happens to be sticking in the circuit-closing position, no other harm is produced than that all the lamps 3, 7 and 17 continue to burn.

95 When the metal bars 5 and 6 as well as the bars 15 and 16 are made of one and the same metal, the result is attained that the apparatus acts independently of the outer temperature and without being affected by the apparatus having become heated by having been used several times at short intervals.

100 105 If necessary, the bars 6 and 16 may be insulated against heat action, for instance by being wound by or inclosed in some heat-insulating substance, or by being made narrower than the bars 5 and 15, so that the latter protect them against the radiating heat.

110 A slower cooling of the bars 5 and 15, if desired, may be attained by insulating them on the side not facing the lamps.

Instead of the heat-operated devices 5, 6 and 15, 16 there may be used heat-operated devices of any suitable construction, where a heating and subsequent cooling causes a circuit to be closed and broken, respectively.

The apparatus described is free of the relatively expensive and unreliable clock-works and also of electro-magnets, and it fills all the requirements to be made to a 10 time switch, in respect to simplicity of construction, cheapness and reliability of performance.

The main condition for attaining the high efficiency in such simple apparatus is the 15 nearly instantaneous heating of the bars 15 and 5 caused by the radiating heat from the incandescent lamps 17 and 7, in connection with the subsequent very slow cooling.

Having now particularly described and 20 ascertained the nature of my said invention and in what manner the same is to be performed, I declare that what I claim is:—

In an electrical time switch, a circuit hav-

ing an electrical heat-emitting member, a second circuit having a thermal expansible 21 circuit-closing element in operative relation to the aforesaid heat-emitting member of the first circuit, said second circuit having also an electrical heat-emitting member, a main circuit having a thermal expansible 30 circuit-closing element in operative relation to said heat-emitting member of said second circuit, and means for breaking said first circuit, whereby, after the main circuit is closed, it may be broken, after the lapse of a 35 time interval, by the successive automatic cooling of the said circuit-closing elements and the successive automatic breaking of their respective circuits.

In testimony whereof the foregoing specification is signed in the presence of two witnesses.

LAURITZ HARALD JOHAN THEODOR BJØRNSEN.
